United States Patent Office

Des. 193,654

Patented Sept. 25, 1962

193,654

ANIMAL FEEDING TUB

Noble Van Voorhis, Los Angeles, Calif., assignor to
Carnation Company, Los Angeles, Calif., a corporation
of Delaware

Filed Feb. 12, 1962, Ser. No. 68,770

Term of patent 14 years

(Cl. D12—2)

FIG. 1.

FIG. 2.

FIG. 1 is a perspective view of the animal feeding tub showing my new design.

FIG. 2 is a side elevational view thereof taken in the direction of arrow 2 in FIG. 1.

I claim:

The ornamental design for an animal feeding tub, as shown.
